CLAIM

The ornamental design for a handle for glass fireplace screen, as shown.

DESCRIPTION

FIG. 1 is a perspective view of a handle for glass fireplace screen showing my new design;
FIG. 2 is an end elevational view thereof, the end opposite being identical;
FIG. 3 is a side elevational view thereof, the side opposite being identical;
FIG. 4 is a top plan view thereof;
FIG. 5 is a bottom plan view thereof.
